UNITED STATES PATENT OFFICE.

EDWIN LANE, OF NEW YORK, N. Y., ASSIGNOR TO CAROLYN LAUNDRY, OF NEW YORK, N. Y., A CORPORATION OF NEW YORK.

TRAY AND SUPPORT FOR LAUNDRY MARKERS.

Application filed December 19, 1923. Serial No. 681,640.

To all whom it may concern:

Be it known that I, EDWIN LANE, a citizen of the United States, residing at New York, in the county of New York and State 5 of New York, have invented new and useful Improvements in Trays and Supports for Laundry Markers, of which the following is a specification.

This invention relates to a tray and holding means for laundry markers, and the primary object of the same is to provide an easily handled retaining and storing device for groups of laundry markers bearing the same identifying character or number 10 15 and whereby the markers may be so disposed that they may be quickly applied to and removed from the tray and the number of each group used in marking the articles or pieces of one ownership readily determined with accuracy without requiring a 20 count of the pieces, thereby saving time and labor in marking articles to be subjected to laundry, dry cleaning or dyeing operations. A further object of the invention is to provide 25 means for conveniently storing groups of laundry markers to facilitate repeated use thereof, each tray so holding the markers intact therewith that the markers may be readily inspected and the identifying 30 numbers or characters thereon ascertained. A still further object of the invention is to generally expedite the marking of articles or pieces for laundry, dry cleaning or dyeing purposes and also to save labor ordinarily required in applying and removing as 35 well as storing groups of marking devices for identifying articles or pieces to be cleaned and assorted.

The invention consists in the construction 40 and arrangement of the several parts which will be more fully hereinafter described and claimed in preferred form.

In the drawing:

Figure 1 is a plan view of a tray and holder embodying the features of the invention and showing one of the markers applied thereto.

Figure 2 is a longitudinal vertical section taken in the plane of the line 2-2, Figure 50 1.

Figure 3 is a transverse vertical section taken in the plane of the line 3-3, Figure 1.

Figure 4 is a detail perspective view of a 55 portion of the tray and holder.

The numeral 5 designates the holder which consists of a flat metal plate having opposite inwardly bent guide flanges or guides 6 centrally intersected by securing ears 7. The guides 6 terminate at their outer ends at a suitable distance from the ends of the plate and the latter are formed with laterally projecting securing extensions or ears 8. The one end 9 of the plate or holder has a stop 10 struck upwardly therefrom at right angles and centrally located. The ears 7 and 8 are all formed with suitable openings 11 for the reception of fastening devices 12, as shown by Figure 3, for the purpose of securing the holder to a 60 65 table, shelf or other support 13. The outer terminals of the flanges or guides 6 are fully open and the holder is without obstruction between the flanges and at one end, the stop 10 providing an obstruction at the remaining end. Any number of these holders may be used for different operations, but each holder is adapted to removably receive any 70 75 number of marker retaining trays 14 consisting of flat sheet-metal plates of suitable 80 thickness and of such dimensions as to easily slide into and outwardly from the flanges or guides 6, each tray 14 when fully inserted in the holder 5 having one end 85 thereof abutting against the stop 10 as clearly shown by Figures 1 and 2. All of the trays are of similar construction and each will be preferably provided with the same number of means for retaining laundry markers in connection therewith and 90 in such manner that said markers may be easily associated with or removed from said means. Numerous devices might be provided for holding the markers in such position 95 relatively to each tray as to facilitate stored application or removal of the markers relatively to the trays, and it is proposed and should be understood that any means adapted to the purpose will be employed and the means which will be presently specifically explained may be modified at will. The essential feature of the invention, therefore, is the provision of a tray having sliding association or retaining engagement 100 with a holder therefor and provided with suitable means for carrying a plurality of markers thereon in such positions that the markers may be easily applied to or removed from the tray. The preferred means for retaining the markers in connection with 105 110

the tray, as shown in the present instance, consists of upwardly projecting retainers 15 cut from the metal of the tray and struck upwardly at oblique angles. Each retainer 15 is centrally corrugated or arched as at 16 to strengthen and stiffen the same sufficiently to resist bending thereof under considerable stress, and to render the same more durable for continued use. The corrugations 16 also provide opposite slide flanges 17 which conjointly act in pairs to receive opposite portions of the markers 18 as shown by Figures 1 and 4, the said markers in the present instance, being shown 15 as having lateral extensions 19 which readily fit behind the successive arched retainers. The distance apart of the slide flanges 17 is such that the retaining means of the markers will not be engaged or injured by 20 the pressure thereof in the flanges, and furthermore, the said flanges are of such thickness that they will not injuriously strain or deteriorate the requisite spring action of the members of the marker. Furthermore, 25 the flanges 17 of adjacent retainers 15 and side terminals of the corrugations or arches 16 of adjacent retainers 15 are such distance apart as to just permit the marker to be inserted therebetween and in engagement 30 therewith, and thereby hold each marker against lateral movement or displacement therefrom and requiring that the markers be applied to and removed from the flanges 17 from the upper terminals of the latter 35 and thus always dispose the markers at the same angle as the retainers which they engage for convenience in discerning the identifying numbers or characters on the markers. The tray is also provided with 40 a series of consecutive numerals, as at 20, in rear of the retainers, these numerals beginning with "1" at the first retainer of the outermost longitudinal line of retainers and continuing consecutively as shown by 45 Figure 1. The tray, as shown in the present instance, is adapted to carry thirty markers, the numerals being disposed opposite the spaces between the retainers, and the purpose of this consecutive numbering of the 50 retainers is to enable the operator to quickly determine how many markers of each group have been used, whether all or only a part of the markers of each group are removed from the tray. This serves as a convenient 55 check to assist the operator in ascertaining the number of pieces that have been marked or the number of markers used in connection with each group of pieces to be laundered or cleaned.

60 From the foregoing, the operation of the improved holder and tray will be readily understood. When it is desired to use a tray containing markers of a certain identifying number or character, the tray is selected carrying markers of the desired

number and inserted in the holder as shown by Figure 1. The operator then removes the markers, beginning with that numbered "1" and continuing, consecutively, until all the markers necessary for providing a certain group of articles or pieces with similar identifying means have been exhausted, and if any of the markers remain on the tray the operator will be positively informed as to the number of pieces marked and likewise in removing the markers from articles or pieces and replacing them on the tray a tally may be kept simply by observing the markers as replaced and thus providing an effective simplified record and means for ascertaining with accuracy, not only as to the number of pieces marked, but also as to the number of pieces returned bearing a similar mark and adapted to be assortable ready for parcelling. This simplified method of determining the number of pieces in either event will greatly reduce the clerical work and written and other records now commonly used in laundries or cleaning or dyeing establishments with material saving in labor and expense. After one tray has had the markers partially or completely removed therefrom and the markers applied to the articles which they are intended to identify, the empty tray or a tray with the unused markers thereon may be readily removed from the holder and replaced by another tray carrying markers having a different identifying number or character for use in marking another group or lot of articles or pieces to be laundered, cleaned or dyed. This operation may be carried on indefinitely with material advantages in handling laundry and dry cleaning work. A particular marker has been referred to 105 and illustrated in connection with the tray retainers, but it will be understood that it is proposed to use any form of marker, or that the tray is not limited in its use to any precise form of marker.

What is claimed as new is:—

1. In a device of the class specified, a flat open-top fixed holder, and a tray slidably and removably engaging the holder and provided with upwardly inclined laundry marker projections disposed in individual spaced relation for engagement by laundry markers which are removably applied to the adjacent side edges of said projections in the spaces between the latter.
2. In a device of the class specified, an open top flat fixed holder, and a tray removably engaging the holder and formed with longitudinal rows of upwardly extending angularly disposed spaced projections having straight side edges and central corrugations for removably receiving and retaining laundry markers thereon which are applied to the said side edges and in the spaces between the projections.

3. A tray for holding laundry markers provided with a plurality of upwardly inclined projections with opposite straight side flanges to removably receive and hold a plurality of markers at the same angle as the projections, the markers occupying the spaces between the projections, the projections being also provided with means for holding the markers against lateral movement when disposed therebetween.

4. A tray for holding laundry markers having a plurality of alined projections each formed with a central corrugation and opposite slide flanges, the projections extending above the tray being uniformly disposed in spaced relation and in alinement to receive and hold the markers therebetween.

5. A tray for holding laundry markers having a plurality of upstanding inclined projections with opposite straight side flanges separated by uniform spaces between them, the projections being disposed in longitudinal rows, the tray being provided with consecutive numerals adjacent to and opposite the spaces and corresponding to the number of projections and holding capacity of the tray.

6. A tray having upstanding inclined projections forming a part thereof and provided with straight flanges at opposite side edges, the flanges being in parallel relation and having uniform spaces between them, the projections being disposed in longitudinal rows, combined with a fixed flat holder into and from which the tray has endwise sliding movement, the holder having means for retaining the tray against movement during

the removal from and application of the markers to said projections, the markers having a straight sliding association and retention relatively to the flanges and filling the spaces between the projections when applied to the latter, the tray being removable from the holder and replaceable by another similar tray to permit the use of markers of different groups having varying indicating numbers.

7. In a device of the class specified, a plurality of laundry markers having uniform indicating numbers, a fixed holder, and a tray removably inserted in the holder and having upstanding inclined projections arranged in distinct longitudinal rows with uniform spaces between the side edges of each two projections throughout the whole series of the latter to regularly receive the laundry markers which are caused to engage the side edges of the projections and be disposed at the same angle of inclination as the latter and held against lateral displacement by the projections, the spaces between the side edges of the projections being supplied with consecutive indicating numbers corresponding to the indicating numbers of the markers disposed in the said spaces and in engagement with the projections and whereby the number of markers in use of each group may be readily ascertained and also permitting the markers to be regularly applied in consecutive order on the projections.

In testimony whereof I have hereunto set my hand.

EDWIN LANE.
